HIGH INTENSITY LUMINOUS TUBE

Richard U. Clark, Fort Wayne, Ind.

Application December 9, 1940, Serial No. 369,145

7 Claims. (Cl. 176—122)

This invention relates to high intensity luminous tubes of the gaseous glow discharge type in which extremely brilliant flashes of light may be produced by the sudden discharge through the tube of large amounts of electrical energy. In general, the chief object of this type of tube is to produce unusually intense illumination for a relatively short period of time in order to brilliantly illuminate objects which would normally require a tremendous amount of illumination for a brief period in order to make them highly visible, as for example, in the illumination of objects which are moving at high speed and also for other purposes where the object must be brightly illuminated in order to bring out suitable contrast between various portions of the subject as, for instance, in the case of still photography of living subjects.

Heretofore, in tubes designed for the above purpose, the chief difficulty has been in originating a tube that will give an extremely high intensity of light and at the same time a relatively long useful life. It has also been found very difficult to produce a tube of the gas discharge type that will maintain its starting and operating voltages reasonably close throughout the life of the tube, in view of the fact that any slight impurity in the gas filling or the presence of occluded gases in the tube structure tend to migrate within the tube and cause fairly wide variations in the operating and arc breakdown voltages.

One object of the present invention is to provide a tube which will avoid the above recited disadvantages.

Furthermore, in prior tubes of the type to which the invention relates, it has been necessary to include a third internal element or control device in order to assist the tube in breaking down electrically through the gas at suitable uniform voltages for commercial use as in certain types of work the breakdown voltage must be fairly constant to give an even timing of the light operation.

A further object of the invention is to provide a tube which has but two active electrodes, the third element mentioned above being dispensed with, this in turn providing a simpler and less costly structure.

With the above and other objects in view, the invention will now be described with reference to the accompanying drawing, in which:

Fig. 1 is a central vertical sectional view through a tube constructed according to the present invention;

Fig. 2 is a horizontal section taken on the line 2—2 of Fig. 1; and

Fig. 3 is a similar view of Fig. 1 showing a modification.

In the drawing, the reference numeral 1 indicates the envelope of the tube which may be of glass or any other suitable material; 2 is the re-entrant portion thereof; 3 and 4 the lead wires which are sealed within the re-entrant portion 2 and at their inner ends are respectively connected to the anode 5 and the cathode 6.

The anode 5 is, in accordance with the invention, made of porous metal composed of suitable gettering metal particles. To form the anode the particles are pressed into the desired shape under high pressure and sintered in a vacuum so as to be relatively gas free and in order to make them adhere firmly to each other.

In using gettering metals for the formation of the anode, I have found columbium metal powders in the above form to be usually effective in that their employment results in maintaining the tube in condition to give a relatively constant breakdown voltage. The importance of utilizing an anode of this type will accordingly at once be appreciated by those skilled in the art.

In operation it has been found that the particular type of anode electrode above described keeps the gas within the device or tube pure and that said device or tube then functions in a relatively uniform manner throughout an unusually long period of time.

The cathode element 6 may take any suitable form and for many types of service may consist merely of an ordinary metallic wire of sufficient bulk to prevent excessive sputtering under the conditions of operation for which it is to be employed. For special purposes, the cathode may be activated or coated with various alkali metals or otherwise made highly active. Although a cold cathode structure is preferred, it is obvious that a heated cathode may be substituted.

The cathode 6 is enclosed in a housing member which may conveniently take the form of a constricted tube 7 of suitable transparent material such as glass, silica or the like, and which preferably extends from the upper surface of the re-entrant portion 2 to a short distance below the upper wall of the envelope as shown in the drawing. The cathode tube 7 is open at its upper end and acts to conduct or guide an extremely intense discharge into the envelope through its said open end.

The cathode tube 7 is preferably suitably crooked or bent, as shown at 8, to prevent the

spread of sputtering from the cathode through the entire length of said tube 7.

To further eliminate the possibility of sputtering spread a desirable form of strainer or baffle 9 may be positioned within the cathode tube 7 as shown in Fig. 3. This strainer or baffle may be of metal or other suitable material and is preferably so fabricated as to allow the discharge to pass whilst preventing the flow of small metal particles.

To further improve the effectiveness of the baffle it may be fabricated of magnetic materials of the more modern types which may be highly magnetized. In conjunction with such a magnetized strainer or baffle a cathode material may be employed of a nature such that when cathode sputtering occurs the magnetic metal cathode particles will be attracted and cling to the baffle permanently.

As will, of course, be understood, the envelope is filled with a suitable gas of a nature such that a high intensity discharge can be obtained. Neon, xenon and mixtures of xenon and krypton have been successfully used, the latter mixture being preferred because it offers better light intensity possibilities at a given cost.

The envelope is normally filled to a relatively high pressure. In many of the devices already tested, pressures of the order of ten to thirty millimeters have been employed but it is understood that there is no reason why the device should be limited to any close range of pressures as it will operate throughout a very wide range, provided suitable input voltages are used. I may also employ an ionizable vapor.

The electrodes are normally supplied with voltage from a condenser or similar storage device and the ignition is excited by means of an external surge of current of high intensity, the same being applied externally to the glass and to one of the inner electrodes of the tube through suitable connections.

Under operating conditions the device or tube may be run at intermittent frequencies covering relatively long periods or may be operated up to frequencies of many hundred per second or more when desired and suitably designed.

For operation through quite a wide range of frequencies the device can be run as a diode oscillator without the need of any external triggering device. Under conditions of relatively high frequency of operation, I have found the crook or bend in the inner tube 7 at point 8 is very desirable to help prevent the spread of sputtering and I have also found that by making this bend relatively sharp so that the upper end of the tube is rather well shielded from the end of the cathode, that the spread of sputtering is very well controlled. One reason for desiring to control the spread of sputtering is to prevent the tendency to lower the breakdown voltage of the tube which is incident to such spread. This is in addition to the desire to keep the inner tube relatively clean for optical reasons.

In this type of tube I have also successfully employed cathodes of columbium metal which I find do not cause a very opaque film under conditions where the columbium cathode tends to sputter. This is particularly true where very

high intensity or high powered disruptive discharges are used as the metal tends to come off in granular form rather than in the form of very finely divided parts, particularly where a porous columbium cathode is used.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. A high intensity luminous tube consisting in a gas filled envelope and an anode and cathode sealed within said envelope, said anode being entirely of porous metal composed of non-alkali gettering sintered metal particles.
2. A high intensity luminous tube consisting in a gas filled envelope and an anode and cathode sealed within said envelope, said anode being entirely composed of a self-supporting mass of columbium sintered metal powders to prevent the fouling of said tube.
3. A high intensity luminous tube comprising a gas-filled envelope, a porous columbium anode, a cathode sealed within said envelope and an inner tube opening into said envelope surrounding said cathode, said inner tube having a sharp bend therein near said cathode.
4. A high intensity luminous tube comprising a gas filled envelope; an anode and a cathode sealed within said envelope, a partial enclosure insulating tube surrounding said cathode, and a tapered helical wire baffle in said cathode enclosure tube for preventing the spread of sputtering from the cathode within said tube.
5. A high intensity luminous tube comprising a gas filled envelope; an anode and a cathode of magnetic material sealed within said envelope, a partial enclosure insulating tube surrounding said cathode, and a magnetized strainer in said cathode enclosure tube for preventing the spread of sputtering from the cathode by its magnetic attraction for said sputter.
6. A high intensity luminous tube comprising a transparent gas filled envelope, a re-entrant stem, leads through said stem, a columbium cathode attached to one lead, a constricted crooked transparent tube surrounding said cathode and extending at least beyond the end of said cathode, and a porous sintered columbium anode adjacent the end of said crooked tube most remote from said cathode, said crooked tube being open at the anode end.
7. A vapor electric luminous tube, said tube encompassing a columbium cathode and porous columbium anode, a re-entrant stem in said tube for supporting said electrodes, an extension of part of said stem around said cathode within said tube to a point beyond the end of said cathode with clearance all around said cathode and a crook in said extension to prevent the spread of opaquing sputter from said cathode combined with an open end in said extension terminating adjacent said anode said anode constantly gettering said tube and said cathode material sputtering easily baffled particles.
